CLAIM

The ornamental design for an ultrasound probe charger as shown and described.

DESCRIPTION

FIG. 1 is a top-front-left perspective view of an ultrasound probe charger according to the claimed design.

FIG. 2 is a top view of the ultrasound probe charger of FIG. 1.

FIG. 3 is a bottom view of the ultrasound probe charger of FIG. 1.

FIG. 4 is a right side view of the ultrasound probe charger of FIG. 1.

FIG. 5 is a left side view of the ultrasound probe charger of FIG. 1.

FIG. 6 is a front view of the ultrasound probe charger of FIG. 1.

FIG. 7 is a rear view of the ultrasound probe charger of FIG. 1.

FIG. 8 is a sectional view of the ultrasound probe charger of FIG. 1 taken along line 8-8 in FIG. 2.

FIG. 9 is a top-front-right view of the ultrasound probe charger, shown in a state of use; and,

FIG. 10 is a bottom-rear-left perspective view thereof.

The dash-dash broken lines in the drawings illustrate portions of the ultrasound probe charger that form no part of the claimed design.

The dash-dot broken lines in FIG. 2 indicating the sectional view form no part of the claimed design.

The ultrasound probe in FIGS. 9 and 10 is environmental subject matter and forms no part of the claimed design.

1 Claim, 8 Drawing Sheets
